RESTRICTOR DEVICE FOR REFRIGERATING APPARATUS

Sylvester M. Schweller, Dayton, Ohio, assignor to
General Motors Corporation, Dayton, Ohio, a
corporation of Delaware

Application December 26, 1944, Serial No. 569,682

2 Claims. (Cl. 62—8)

1

This invention relates to refrigerating apparatus and particularly to air cooled refrigerating apparatus of the household type.

Due to simplicity in construction and the substantially fool proof characteristics of fixed or continuously open restrictors, this type of restrictor has generally replaced movable valves heretofore employed in refrigerating systems for controlling the flow of liquid refrigerant from the condenser to the evaporator and for causing expansion of liquid refrigerant into the evaporator. While such fixed restrictors have been extensively used they present certain problems which the present invention is adapted to overcome.

In air cooled refrigerating apparatuses, particularly of the household type in which trays containing water to be frozen are placed in the evaporator, the refrigerating mechanism operates efficiently with the employment of a constantly open fixed type restrictor in the system at normal room temperatures. However, this same refrigerator in either of different room temperatures of, say for example, 70° F. and 110° F. will not operate at maximum efficiency particularly when a heavy demand is placed on the evaporator such as the placing of a plurality of trays containing water to be frozen in the evaporator. In other words, a sharp heavy demand on the evaporator of an air cooled refrigerating system, wherein a fixed restrictor is employed, will not be effectively met in a room maintained at either a low temperature or a high temperature because the fixed restrictor together with certain characteristics of the refrigerant liquefying and compressing unit limits maximum efficiency performance of the system. In a low temperature room the compressor unit operates with a low head pressure and with high vacuum low pressure. In a high temperature room the compressor unit operates with a higher head pressure and with a lower vacuum. In other words the pressure differential between the high and low pressure sides of the system is much greater at high room temperatures, than at normal room temperatures, and much lower at low room temperatures. Consequently, if a fixed restrictor is correctly calibrated for normal room temperatures, it feeds too much refrigerant to the evaporator at high room temperatures and not enough at low room temperatures, over and above the change required by heat leakage into the cabinet. In order to overcome this problem I contemplate the use in a refrigerating system of a thermally responsive device and particularly a

2

relatively long capillary flow conduit which is thermally responsive substantially throughout its entire length to condenser refrigerant temperatures and/or to condenser air temperatures to form a compensator cooperating with the refrigerant expander or restrictor to provide the correct flow of refrigerant under varying room temperatures.

An object of my invention is to provide a means particularly in a refrigerating apparatus employing a fixed or continuously open restrictor which will compensate for abnormal temperatures in the room in which the refrigerator is located to thereby render operating conditions of the refrigerant compressing and liquefying unit of the apparatus uniform and more efficient.

Another object of my invention is to provide means for varying the flow of refrigerant from a refrigerant compressing and liquefying unit of a refrigerating system to a fixed or continuously open restrictor employed in the system so as to permit the proper amount of liquid refrigerant to flow through the restrictor at all times irrespective of ambient temperatures within the room in which the refrigerator is located.

A further object of my invention is to provide a means for changing the cross-sectional area of a capillary passage in the liquid refrigerant supply line of a refrigerating system to vary the flow of refrigerant to the expansion element or fixed restrictor which means is rendered effective automatically in response to temperature changes.

In carrying out the foregoing objects, it is a still further and more specific object of my invention to provide a means in the liquid refrigerant supply line of a refrigerating system which means is constructed of metals of different coefficient of expansion and contraction and which means is provided with a continuously open substantially capillary passage the cross-sectional contour or area of which is reduced and increased in response to an increase and decrease in temperature respectively for varying the flow of liquid refrigerant through the supply line.

Further objects and advantages of the present invention will be apparent from the following description, reference being had to the accompanying drawings, wherein a preferred form of the present invention is clearly shown.

In the drawings:

Fig. 1 is a vertical sectional view of a refrigerating apparatus having a refrigerating system embodying my invention associated therewith;

Fig. 2 is an enlarged view of a compensating

device constructed in accordance with my invention and which is interposed in the refrigerating system of the apparatus disclosed in Fig. 1;

Fig. 3 is an enlarged sectional view of a portion of the compensating device taken on the line 3—3 of Fig. 2; and

Fig. 4 is a view similar to Fig. 3 showing the area of the passage in the compensating device diminished.

In Fig. 1 of the drawings I have shown a refrigerating apparatus of the household type comprising a cabinet 10 having insulated walls 11 forming a food storage compartment 12 therein and other walls forming a machine compartment 13 below the compartment 12. A closed refrigerant circulating system or circuit is associated with cabinet 10 and has its refrigerant compressing and liquefying unit mounted in the machine compartment 13. This refrigerant compressing and liquefying unit comprises a sealed motor-compressor 14 for compressing refrigerant and for forwarding the compressed refrigerant under pressure to a condenser 15 wherein the compressed refrigerant is cooled, liquefied and collected. From the condenser 15 the liquid refrigerant is forwarded through a supply line or conduit 16 to a restrictor 17 from where it is expanded into a cooling element or evaporator 18. The evaporator 18 is mounted in the upper portion of the food compartment 12 which is to be cooled. The evaporator 18 may be of the sheet metal variety and is provided with a refrigerated shelf 19 adapted to receive a tray or trays containing water to be frozen into ice cubes or blocks as is conventional in the art. Vaporization of the refrigerant takes place in the evaporator 18 and the evaporated refrigerant returns to the compressor 14 through the suction line or conduit 20. In order to provide for intermittent operation of the motor-compressor 14 a thermostatic switch (not shown) actuated in response to the refrigerating effect produced by evaporator 18 may be connected into the electric circuit leading to the motor-compressor 14. The method of actuating such a switch by a thermostat bulb is conventional and it is not believed necessary to describe same herein.

The restrictor 17 is of the fixed continuously or constantly open type, well known in the art, and since the difficulties hereinbefore set forth arise with the use of this type of expansion element or restrictor, it is desirable to employ in the refrigerating system some means for changing the effect produced in the refrigerating system in response to ambient temperatures. To this end I interpose in the liquid refrigerant supply line or conduit 16, adjacent condenser 15 and within the machine compartment 13, a compensating means in the form of a restrictor device 31 (see Fig. 1). The compensator or restrictor 31 is shown on a larger scale in Fig. 2 of the drawings and comprises a small metal rod or wire 33 (see Fig. 3) enclosed in a metal sheet or tube 34.

The metal rod or wire 33 is slit longitudinally to provide a narrow substantially U-shaped groove 36 extending from end to end thereof. The tube 34 comprises a metal sheet wrapped around rod 33 with its edges 37 welded or brazed together to form a confining sleeve or the tube 34 for the rod. Tube 34 has a minor portion of its interior surface brazed or welded to rod or wire 33 as indicated by the heavy line 38 in the drawing which is only slightly beyond the tube edges 37. The tube 34 is normally of a larger inside diameter than the outside diameter of the wire so

that wire 33 will be spaced therefrom throughout a substantial portion of the circumference thereof to allow ample expansion of the wire 33. The space between wire 33 and tube 34 together with the U-shaped groove 36 forms a small or capillary passage of great length as compared to its cross-sectional area extending through the device 31 so as to communicate with the interior of the refrigerant supply line or conduit 16 in which the device 31 may be securely interposed. Wire 33 and tube 34, are formed of metal having a different coefficient of expansion and contraction relative to one another so as to be differently responsive to temperature changes. For example, the wire 33 may be formed of brass or aluminum while the sleeve or tube 34 may be formed of stainless steel. The temperature of refrigerant leaving the condenser and/or the temperature of air leaving the condenser may affect the device 31. Due to the different coefficient of expansion of the elements of device 31 warming thereof will cause expansion of rod or wire 33 within the sleeve or tube 34 to close off the space intermediate the rod 33 and the inner wall of sleeve 34, as is shown in Fig. 4 of the drawings, to thereby reduce the cross-sectional area of the capillary passage through the device. Obviously when the device 31 is cooled wire 33 will contract and increase the cross-sectional area of the refrigerant flow passageway extending therethrough.

The single passage in device 31 within the line or conduit 16 may normally offer the proper resistance to control the flow of liquid refrigerant through this line. For example, flow of liquid refrigerant from the refrigerant compressing and liquefying unit to the restrictor 17, of the refrigerating system shown in Fig. 1, may be proper at ordinary temperatures, maintained in a room in which the refrigerating apparatus is located, in accordance with the usual or normal pressures in the system. However, an abnormal rise in temperature within the room, such as a period of several days of very hot weather and particularly at the time a large amount of water is placed in the evaporator to be frozen, will cause the temperature and consequently the pressure of refrigerant in the condenser to increase. Without some means of controlling or varying the flow of refrigerant from the refrigerant compressing and liquefying unit too much liquid refrigerant will be forced from condenser 15 to and through restrictor 17 into the evaporator 18. My invention eliminates the difficulties hereinbefore pointed out in that when this abnormal high temperature occurs the passage in the compensating device or second restrictor 31 automatically offers more resistance to the flow of refrigerant to the restrictor 17 to thereby prevent too great amount of liquid refrigerant flowing therethrough and into the evaporator. At abnormal low room temperatures or installation of a refrigerator in a cool pantry or the like, the compensating device or second restrictor 31 automatically offers less resistance to the flow of refrigerant into the evaporator and ample refrigerant is maintained in the evaporator to prevent the high suction force of the refrigerant compressing and liquefying unit from robbing or starving the evaporator of refrigerant and thereby the evaporator functions to effectively meet any demand placed upon it. The temperatures are transmitted through walls of the device 31 from exteriorly thereof and also by refrigerant flowing to and through the passage of the device. Due to the confinement of rod or wire 33 within sleeve 34 together with the fact

that wire 33 is welded to the sleeve 34 only at its edges and slightly therebeyond and the difference in coefficient of expansion and contraction of these members the heat will expand the wire 33 to cause it to diminish the cross-sectional area of the passage between the wire and its enclosing sleeve (see Fig. 3) as disclosed in Fig. 4. In this compensating device or restrictor 31 refrigerant flows only through its narrow U-shaped capillary passage, provided by the slit or cut 36, when the rod or wire 33 is fully expanded. In this manner greater resistance to the flow of liquid refrigerant from the condenser to the restrictor and to the evaporator is afforded to prevent higher pressures in the system from circulating too much refrigerant through the restrictor 17. If the temperature externally of the refrigerator increases abnormally the temperature and consequently the pressure of refrigerant in the condenser simultaneously increases and both these temperatures cause a reduction in the size or cross-sectional area of the capillary passage in device 31. The additional restricted flow or the increase of flow, as the case may be, of liquid refrigerant to the restrictor 17 and into evaporator 18 counterbalances or compensates for the increase or decrease of refrigerant pressure within the system to thereby eliminate the difficulties hereinbefore enumerated and provide efficient operation of the refrigerating system irrespective of ambient temperatures.

It will be seen that my improvement of providing a compensating device in which a fixed continuously open refrigerant flow passage there-through has its cross-sectional area changed or varied, by metal members having different coefficient of expansion and contraction relative to one another, I eliminate the use of movable valves or the like and the use of other materials in such an arrangement which might become inoperative through deterioration by the refrigerant within the system. My improved compensating device is simple in construction and can be added or interposed in a refrigerating system without materially increasing the cost thereof.

While the form of embodiment of the invention as herein disclosed constitutes a preferred form, it is to be understood that other forms might be adopted, as may come within the scope of the claims which follow:

What is claimed is as follows:

1. A refrigerating apparatus comprising, a temperature responsive refrigerant flow compensat-

ing device, a compressor unit having a condenser connected to one end of said device, a fixed restrictor connected to the other end of said device and an evaporator between said fixed restrictor and said unit, said compensating device including a metal tube member and a metal rod member secured therein, said rod member normally being slightly smaller in diameter than the inside diameter of said tube member to form a capillary passageway throughout the length of said device, the exterior of said device being in contact with air in the vicinity of said condenser and the interior of said device being in contact with high side refrigerant leaving said condenser, and one of said members of said device having a greater coefficient of expansion and contraction than the other thereof for varying the cross-sectional area of said passageway to control the amount of high side refrigerant admitted to said fixed restrictor.

2. A refrigerating apparatus comprising, a temperature responsive refrigerant flow compensating device, a compressor unit having a condenser connected to one end of said device, a fixed restrictor connected to the other end of said device and an evaporator between said fixed restrictor and said unit, said compensating device including a metal tube member and a metal rod member secured therein, said rod member having a groove therein forming a capillary passageway throughout the length of said device, the exterior of said device being in contact with air in the vicinity of said condenser and the interior of said device being in contact with high side refrigerant leaving said condenser, and said rod member of said device having a greater coefficient of expansion and contraction than the tube member thereof for varying the cross-sectional area of said passageway to control the amount of high side refrigerant admitted to said fixed restrictor.
